United States Patent Office

Des. 211,254
Patented June 4, 1968

211,254

SPEAKER ENCLOSURE

Aston L. Moore, 220 Hammond Place,
South Bend, Ind. 46601

Filed Oct. 13, 1967, Ser. No. 8,991

Term of patent 14 years

(Cl. D26—14)

FIG. 1

FIG. 2

FIG. 3

FIG. 4

FIG. 5

FIG. 6

FIG. 7

FIG. 8

FIGURE 1 is a top, perspective view of a speaker enclosure showing my new design;

FIGURE 2 is a side elevational view thereof, the opposite side being substantially a mirror image thereof;

FIGURE 3 is a bottom plan view thereof;

FIGURE 4 is a top plan view thereof;

FIGURE 5 is a top perspective view of a speaker enclosure showing a modification of my new design;

FIGURE 6 is a side elevational view thereof, the opposite side being substantially a mirror image thereof;

FIGURE 7 is a bottom plan view thereof; and

FIGURE 8 is a top plan view thereof.

I claim:

The ornamental design for a speaker enclosure, as shown and described.
